UNITED STATES PATENT OFFICE.

JACOB B. CONOVER, OF JERSEY CITY, NEW JERSEY.

CAN-SMOOTHING MACHINE.

1,113,196.

Specification of Letters Patent.

Patented Oct. 13, 1914.

Application filed June 28, 1911. Serial No. 635,388.

To all whom it may concern:

Be it known that I, JACOB B. CONOVER, a citizen of the United States, residing at Jersey City, in the county of Hudson and State of New Jersey, have invented certain new and useful Improvements in Can-Smoothing Machines, of which the following is a specification, reference being had therein to the accompanying drawings, forming part 10 thereof.

My invention relates to smoothing machines for removing the dents of usage from milk cans and ice cream cans. The quick and rough handling of these cans in transportation in their travels back and forth frequently results in the denting or crushing in at various places of the cylindrical sides of the cans. This not only defaces the cans but diminishes or varies their capacity.

20 The object of my invention is to quickly and effectively smooth out these dents in the can sides and thereby restore the cans substantially to their original appearance and capacity.

25 My invention includes means for pressing the cylindrical wall of the can between smoothing rollers.

My invention more particularly includes a continuously driven pressure roller relatively movable to and from coactive relation with an idler can-supporting roller, so that the can is circumferentially fed only when the rollers are in coactive relation.

35 My invention also includes other features of construction and combination of parts, as will hereinafter appear.

I shall now describe the can smoothing machine embodying my invention which is illustrated in the accompanying drawings 40 and shall thereafter point out my invention in claims.

Figure 1 is a side elevation, partly in section, of the can smoothing machine, shown as arranged for hand actuation. Fig. 2 is 45 a front elevation, viewed from the right in Fig. 1, but shown as arranged to be driven by power. Fig. 3 is a detail elevation showing how a can body is operated on.

The can smoothing machine shown in the 50 drawings has a frame comprising a can-re-

ceiving horn 1, a carrier-supporting bracket or hanger 2 provided with a brace 3, and a vertical supporting plate 4. The horn 1, the hanger 2 and the brace 3 may be secured to the support 4 by bolts, as shown, and the 55 machine may be mounted on a wall or post with the support 4 in vertical position, as shown in the drawings.

The outer portion of the can-receiving horn 1 is offset upwardly, as shown, and such outer portion is provided on its upper side with a hard metal can-supporting roller 5 which projects upwardly above the horn 1. The horn 1 supports the roller 5 at both ends of the roller, and the roller is shown 65 as having a shaft 6 journaled in bearings in the horn. To permit the smoothing of the extreme inner portions of the can cylinder, a short supplemental can-supporting roller 7 projects beyond the outer end of the horn 1 in alinement with the main can-supporting roller 5 and is shown as carried by the outer end of the roller shaft 6 beyond its outer bearing. The horn 1 may enter a milk can or an ice cream can and support the can 75 from the inside upon the rollers 5 and 7. The upward offsetting of the outer roller-carrying portions of the horn 1 permits the can-supporting rollers to support cans having reduced upper portions and necks of 80 smaller diameter than the cylindrical bodies of the cans, such, for example, as the usual New York milk cans. The can-supporting rollers 5 and 7 are idler rollers upon which a can may stationarily rest preparatory to 85 being operated upon or for removal after being operated upon.

A drive shaft or actuating shaft 8 is journaled in bearings in the lower side of the hanger 2 and substantially in vertical alinement with the can-supporting rollers 5 and 7 and parallel thereto. The actuating shaft 8 is arranged to be driven from any convenient source of power by means of a belt pulley 9 upon the inner end of such shaft, 95 and a belt 10, as shown in Fig. 2; or by hand by means of a crank 11 applied to the squared outer end of this shaft, as shown in Fig. 1.

A swinging roller-carrier 12 is pivoted to 100

swing about an axis coincident with the axis of the actuating shaft 8, and is shown as pivoted directly on such shaft adjacent to the shaft bearings of the hanger 2. The 5 carrier 12 is of widened H-shape, having comparatively short end bars or legs and a lengthened cross-bar or connecting bar, and is shown as formed in one piece.

A roller shaft 13 is journaled in the lower 10 portion of the swinging roller-carrier 12, in parallel relation with the actuating shaft 8, and mechanical connections are provided between the actuating shaft 8 and the roller shaft 9 for actuating the latter from the 15 former, such connections comprising a pair of intermeshing spur gears 14 fixed respectively on the shafts 8 and 13.

A pressure roller 15, coactive with the can-supporting rollers 5 and 7 to smooth the 20 can cylinder, is mounted on the roller shaft 13 for rotation thereby. The pressure roller 15 is shorter than the space between the 25 bearings for its shaft 13, and is connected to its shaft by a spline 18 so as to be compelled to rotate with the shaft. A screw 30 plug 16 and wedge 17 are provided for fixing the pressure roller 15 at any desired position of adjustment along the roller shaft 13. Longitudinal movement of the roller 35 shaft 13 is prevented by the gear 14 at its inner end and by a collar 18 at its outer end. The purpose of the longitudinal adjustment of the pressure roller 15 is to provide 40 for the clearance of hoops or other projecting parts at the outside of the can body, such projecting parts commonly occurring adjacent to the ends of the can cylinder. As 45 the actuating shaft 8 is parallel to the can-supporting rollers 5 and 7, and the pressure roller 50 15 is parallel to the actuating shaft 8, and the pressure roller carrier 12 swings on the actuating shaft, the pressure roller 15 is in parallel relation with the can-supporting 55 rollers 5 and 7, and will remain in parallelism thereto as the roller-carrier 12 swings. The relative dimensions and locations of the parts are such that when the roller-carrier 12 is swung downward the pressure roller 15 is thereby brought into 60 proximity to the can-supporting rollers 5 and 7, as shown in all figures of the drawings, to press the wall of a can between the pressure roller 15 and the can-supporting rollers 5 and 7, as shown in Fig. 3.

As means for swinging the roller-carrier 12 to move the pressure roller 15 to and from operative position in relation to the can-supporting rollers, a hand lever 19 is provided, shown as projecting at right angles 65 from the roller-carrier near the outer end thereof. The lever 19 is shown as having a reduced end passing through an eye in the longitudinal bar or cross-bar of the H-shaped

carrier-frame 12 and secured in place by a nut. The lever 19 may be inserted from 65 either side of the roller-carrier 12, to project either to the right or to the left of the machine as viewed in Fig. 2, and is shown in the drawings as projecting to the right. The roller-carrier 12 is adapted to swing in either 70 direction to move the pressure roller 15 away from the can-supporting rollers 5 and 7. When the lever 19 is at the right of the machine, such lever may be raised to swing the roller-carrier 12 to the right and shift 75 the pressure roller 15 to the right and upwardly away from the can-supporting rollers. Were the lever 19 applied at the other side of the machine, the roller-carrier 12 would be swung in the opposite direction 80 to oppositely shift the pressure roller 15 away from the can-supporting rollers. This two-position adjustment of the lever 19 permits the operator to stand at either side of the machine. 85

When the machine is operated by power, as indicated in Fig. 2, the pressure roller 15 may be continuously driven. When the pressure roller 15 is in coactive relation with the can-supporting rollers, with a can in position on the can-supporting rollers, the can cylinder will be fed circumferentially between the rollers, as shown in Fig. 3. The rotation of the pressure roller 15 may be in, either direction, but it is usually preferable 95 to feed the upper surface of the can cylinder away from the operator, as indicated in Fig. 3. When the pressure roller 15 is swung to elevated position, a smoothed can may be removed and replaced by another 100 can to be operated upon. The can just operated upon, will successively rest stationarily on the can-supporting rollers 5 and 7, regardless of the continuous driving of the 105 pressure roller 15.

The swinging roller-carrier 12 is a pressure lever and the pressure applied by its pressure roller 15 is greatly increased at the 110 points of application to the can surface by reason of the angular relation of the pivot of the roller carrier, the axis of the pressure roller 15 and the axis of the can-supporting rollers 5 and 7, this angular relation being indicated by the center lines x , y , in Fig. 3. 115 As will be seen this angular relation is that of the well known and highly powerful toggle joint. The lever 19, of course, further increases the pressure of the rollers on the wall of the can cylinder. 120

Adjustment is provided to secure effective pressure and proper coactive relation of the pressure roller 15 with the can-supporting roller 5, in operating upon different cans having cylindrical walls of different thickness of metal. Such adjustment may be 125

effected by adjusting the distance of one of these rollers from the pivotal axis of the roller-carrier 12, thereby adjusting the relative spacing of these rollers from such pivotal axis. This adjustment is shown as applied to the can-supporting rollers 5 and 7, and is effected by vertically adjusting the can-receiving horn 1 on the supporting plate 4, vertical bolt-receiving slots 20 in the flange of the horn 1 cooperating with the securing bolts for the horn 1 to make provision for this adjustment.

It is obvious that various modifications may be made in the construction shown in the drawings and above particularly described within the principle and scope of my invention.

I claim:

1. A can smoothing machine comprising an idler can-supporting roller for entering a can and supporting it from the inside, a rigid support for the idler can-supporting roller, a rigid carrier-supporting hanger in spaced relation to the can-supporting roller and its support, an actuating shaft journaled in the hanger having its axis in a plane with the axis of the idler can-supporting roller, a swinging roller carrier mounted to swing about the actuating shaft, a roller shaft journaled in the roller-carrier with its axis in a plane with the axis of the actuating shaft, a combined feed roller and pressure roller rotatable with the roller shaft, the latter roller and the idler can-supporting roller having a spaced relation to the actuating shaft such as will provide for the coöperation of these rollers by swinging the roller-carrier about the actuating shaft, mechanical connection between the actuating shaft and the roller shaft for actuating the latter from the former, and manually actuatable means for swinging the roller-carrier to shift the combined feed and pressure roller to or from coactive relation with the idler can-supporting roller.

2. A can smoothing machine comprising an idler can-supporting roller for entering a can and supporting it from the inside, a rigid support for the idler can-supporting roller, a rigid carrier-supporting hanger in spaced relation to the can-supporting roller and its support, an actuating shaft journaled in the hanger above and parallel with the axis of the can-supporting roller, a swinging roller-carrier mounted to swing about the actuating shaft, a roller shaft journaled in the roller-carrier in parallel relation with the actuating shaft, a combined feed roller and pressure roller rotatable with the roller shaft, the latter roller and the idler can-supporting roller being relatively so spaced from the actuating shaft as to provide for the coactive rela-

tion of these rollers through the swinging of the roller-carrier about the actuating shaft, mechanical connection between the actuating shaft and the roller shaft for actuating the latter from the former, and manually actuatable means for swinging the roller-carrier to shift the combined feed and pressure roller to and from coactive relation with the idler can-supporting roller.

3. A can smoothing machine comprising a can-receiving horn, the outer portion of which is offset upwardly, an idler can-supporting roller supported at both its ends on the upwardly offset portion of the horn and projecting above the horn, the horn extending at the outside of the can-supporting roller and having a bearing at its outer end for the outer end of the can-supporting roller, a supplemental idler can-supporting roller projecting beyond the end of the horn concentric with the first can-supporting roller, a carrier-supporting hanger above the horn, an actuating shaft journaled in the hanger above and parallel with the axes of the can-supporting rollers, a swinging roller-carrier mounted to swing about the actuating shaft, a roller shaft journaled in the roller-carrier in parallel relation with the actuating shaft, a combined feed roller and pressure roller rotatable with the roller shaft and adjustable longitudinally thereon, the latter roller and the can-supporting rollers being relatively spaced from the actuating shaft so as to permit their coactive relation through the swinging of the roller-carrier about the actuating shaft, mechanical connection between the actuating shaft and the roller shaft for actuating the latter from the former, and manually actuatable means for swinging the roller-carrier to shift the combined feed and pressure roller to and from coactive relation with the idler can-supporting rollers.

4. A can smoothing machine comprising a can-receiving horn, the outer portion of which is offset upwardly, an idler can-supporting roller supported at both its ends on the upwardly offset portion of the horn and projecting above the horn, the horn extending at the outside of the can-supporting roller and having a bearing at its outer end for the outer end of the can-supporting roller, a carrier-supporting hanger above the horn, an actuating shaft journaled in the hanger above and parallel with the axis of the can-supporting roller, a swinging roller-carrier mounted to swing about the actuating shaft, a roller shaft journaled in the roller-carrier in parallel relation with the actuating shaft, a combined feed roller and pressure roller rotatable with the roller shaft, the latter roller and the can-supporting roller being relatively spaced from the actuating shaft as to provide for the coactive rela-

actuating shaft so as to permit their co-active relation through the swinging of the roller-carrier about the actuating shaft, mechanical connection between the actuating shaft and the roller shaft for actuating the latter from the former, and manually actuatable means for swinging the roller-carrier to shift the combined feed and pres-

sure roller to and from coactive relation with the idler can-supporting roller. 10

In testimony whereof I have affixed my signature in presence of two witnesses.

JACOB B. CONOVER.
